UNITED STATES PATENT OFFICE.

FRANCIS LEROY HORSPOOL, OF SALT LAKE CITY, UTAH.

ROTARY ENGINE.

1,379,028.

Specification of Letters Patent. Patented May 24, 1921.

Application filed May 27, 1919. Serial No. 300,087.

To all whom it may concern:

Be it known that I, FRANCIS LEROY Horspool, a citizen of the United States, residing at Salt Lake City, in the county of Salt Lake and State of Utah, have invented a new and useful Improvement in Rotary Engines, of which the following is a specification.

This invention relates to an improvement in rotary engines suitable to be operated by explosive mixtures of fuel and air, or by the pressure of a steady flow of compressed air, steam or other elastic medium.

While this invention may be operated by any suitable fluid under pressure, it is particularly adapted for operation by explosive mixtures of fuel and air, thereby the invention will be described as an explosive engine.

One object of my invention is to provide an internal combustion rotary engine, with uniform rotative movement without a dead center when two or more explosive chambers are used.

Another object of my invention is to provide an internal combustion rotary engine, whereby the maximum energy of the explosive mixtures upon explosion is obtained.

Another object of my invention is to provide an internal combustion rotary engine, whereby the explosive mixture is compressed within the valve chamber and forced into the explosion chamber.

Another object of my invention is to provide an internal combustion rotary engine that may be driven continuously in one direction or reversed and run in the opposite direction, about a central axis in an endless piston chamber in which the rotary piston is fitted.

With these and other objects in view, my invention consists of the following arrangement of parts, to be hereinafter described and claimed, reference being had to the drawings forming part of this specification and to the figures of reference marked thereon.

Figure 1 is a front view of my invention, the throttle lever 36 being removed.

Fig. 2, is a section on line 2—2 Fig. 1.

Fig. 3, is a section on line 3—3 Fig. 2.

Fig. 4, is a plan view, showing the position of the reversing levers.

Fig. 5, is an enlarged detail on line 5—5

of the rotary piston, showing the piston 55 packing in place.

Fig. 6, is a fragmentary section of the rotary piston showing the packing from the side of the rotary piston.

Fig. 7, is an enlarged view of one section 60 of the rotary piston packing.

Fig. 8, is an enlarged detail view of one of the sliding abutments, with the packing and means for holding same.

Fig. 9, is an end view of Fig. 8.

Fig. 10, is a section looking down on line 10—10 Fig. 1, of the valve cam, showing the taper for operating the piston valve.

Similar letters and numerals refer to like parts throughout the several views of the drawings.

The invention is composed of a casing 1 having a water cooling jacket 2, a base support 3, a front wall 4 having a water cooling space 6 and the back wall 5 which also has a water cooling space 6' the front and back walls are secured into place by means of bolts.

Within the casing 1 and between the front wall 4 and the back wall 5 is located the explosive chamber 7, in which is placed and operated the reversing valve 8 for reversing the travel of the rotary piston. The reversing valve 8 is keyed on the shaft 9 of which one end is journaled in the inner face of the front wall 4 and 4' and the other end passing out through the back wall 5 to which the lever 11 is secured thereto. To the lever 11 is attached to one end of the connecting rod 12, while the other end of the connecting rod 12 is attached to the bell crank lever 13. The bell crank lever 13 is fulcrumed at 14 to the bracket 15 which is secured to the casing 1 and then attached to a sliding bar 16. The bell crank lever 13 when moved operates the connecting rod 12 which operates the reversing valve 8. The bell crank lever also operates the sliding bar 16 which raises and lowers the sliding abutments 17 and 17' by operating under the heads 18 and 18' which are secured on the outer end of the sliding abutment stems 19 and 19'. On the sliding abutment stems 19 and 19' is placed a spiral spring 20 and 20' for holding the sliding abutments 17 and 17' on the periphery of the rotary piston when they are released by the sliding bar 16.

105

I have placed within the grooves cut in the ends of the sliding abutments 17 and 17' packing 21 which is secured therein by a pin passing through the hole 21'. I have also placed another hole 22 lengthwise into which is placed a spiral spring 22' for pressing the packing 21 to the inner face of the front walls 4 and the back wall 5, thus preventing the escape of the explosion back-
ward.

10 A spark plug 23 is placed on the casing 1 and passing through the casing into the explosive chamber 7 for exploding the gases within the explosive chamber.

15 On the front wall 4 is located a projection 10 in which is located the valve chamber 25 and the inlet 40' to the valve chamber. In the valve chamber 25 is placed the bushing 26, the piston valve 27, the packing 28 20 and the gland 29, the gland 29 being screwed into the valve chamber 25.

A bracket 30' is secured to the front wall 4 by means of bolts, a hole is cut in the bracket through which passes the piston 25 valve stem 31 which is secured to the piston valve 27, the bracket 30' is for holding the piston valve stem 31 in line for operation by the valve cam 39.

Attached on the valve stem 31 is one section 30 of the circuit breaker 32, while the other section 33 is secured to the side wall 4 by screws. The wire 34 is attached to the section 32 and to the generator, not shown, and the wire 34' being attached to section 33 and 35 with the spark plug 23 thus completing the electric circuit.

On the projection 10 of the front wall 4 are brackets 30 in which is fulcrumed the throttle lever 36 at 36', which is connected 40 at the lower end to a strap 37 that is placed within the groove 38 that is cut within the valve cam 39 while the upper end is connected to a hand rod 55.

The valve cam 39 is made in such a manner that by operating it on the shaft 41 by the throttle lever 36 it will regulate the travel of the piston valve 26 which in turn will control the flow of explosive gases into the piston valve chamber 25 from the inlet 40'. Within the inlet 40' I have placed a check valve, not shown in the drawings, for preventing the explosive gases being forced back into the feed pipe 40 when the piston valve 27 is being closed by the valve cam 29.

From the piston valve chamber 25 and through the inner face of the front wall 4 into the explosive chamber 7, are port openings 51, through which the explosive gases 60 pass from the piston valve chamber 25 into the explosive chamber 7 when the piston valve 27 is being closed by the operation of the valve cam 39.

The front wall 4 and the back wall 5 an- 65 swer for bearings for the shaft 41. Se-

cured to the shaft 41 is the rotary piston which is constructed in four sections. The sections 43 and 43' are integral with the hub 44 and form one portion of the rotary piston, which does not fill the interior of the 70 casing, thus forming a space within the casing. The sections 46 and 46' are secured to the sections 43 and 43' by bolts. Where the sections 43 and 43' meet the sections 46 and 46' they are tapered so as to form a pocket 75 to receive the full force of the exploded gases from the explosive chamber 7.

The sections 46 and 46' project beyond sections 43 and 43' and completely fill the interior of the casing. 80

To prevent the explosive gases escaping by the rotary piston, I have provided a packing 47 and 47' located within a groove cut in the periphery and down the sides of the sections 46 and 46', the packing 47 and 47' 85 being made in right and left sections. The flat springs 48 and a spiral spring 48' are placed within the groove to keep the upper angle of the packing in contact with the inner radius of the rotary piston chamber. 90 Another spiral spring 49' is placed within a hole drilled through the sections 46 and 46' for pressing the lower angles outward and to keep them in contact with the inner face of the side walls. When the two sections of 95 the packing are placed together the grooves 50 and 50 will form a hole which is for holding oil. On the side angle of the packing 47 and 47' are notches 48'' which are in line with the grooves 48 cut in the side of the rotary piston. The grooves and notches are to fit over the flanges 49 that are located on the inner face of the front and back walls 4 and 5, thus preventing the explosive gases 100 escaping between the side walls and the rotary piston.

Within the casing 1 is located an exhaust port 50 to allow the exploded gases to escape from the rotary piston chamber.

Within the casing are holes 51 which allow 110 the free circulation of water from the front wall through the casing into the back wall when the water is placed within the casing through the holes 52.

Oil is placed within the space A of the rotary piston through the hole 53 which is then plugged by a stud. From the space A it will pass through holes 55 into the casing of the rotary piston. 115

Having described the parts of my invention, I will now illustrate the operation of same. 120

The drawing shows the invention in the position of exploding the gases within the explosive chamber 7. 125

When the gases are exploded within the explosive chamber, they are deflected by the reversing valve 8 into the pocket 45 then back to the check valve 17, thus forcing the rotary piston in the direction of the arrow 130

d. As the rotary piston revolves and the sections 46 and 46' pass the check valve 17 it will be raised up in the socket and remain until the section has passed and then 5 it will be forced down by the spiral spring 20.

After the gases have been exploded and the rotary piston revolves the gases are released through the exhaust port 50.

10 The valve cam revolves with the shaft 41 and the rotary piston. And when the tapered part 53 passes the valve stem 31, the valve stem will be forced down by the spiral spring 32 thus removing the piston valve 27 from the inlet 40' and the port openings 51, thus allowing the combustion gases to enter the piston valve chamber 25 and pass on through the port openings 51 into the explosive chamber 7.

20 When the piston valve 27 starts on the upper stroke the check valve in the inlet 40' will close and the gases within the piston chamber will be compressed into the explosive chamber, and as soon as the piston valve 27 is in full upper stroke, as shown, the circuit breaker will be closed and the gases within the explosive chamber exploded.

To regulate the flow of gases into the piston valve chamber, if more gas is required, move the handle 55 of the throttle lever 36 in the opposite direction of the arrow *f*, this will give the piston valve more travel and allow a longer time for the gases to enter.

35 To decrease the flow of gas into the piston valve chamber, move the throttle lever in the direction of the arrow *f*, this will give the piston valve shorter travel by traveling over the larger radius of the valve cam.

40 To give the throttle lever full throw in the direction of the arrow *j* it will move the valve cam in the direction of the arrow *g* thus causing the valve stem 31 to ride on the radius of the valve cam so that it will not 45 drop into the taper 53' and the piston valve will be held as shown and the inlet 40' will be closed, thus stopping the engine.

To reverse the direction of the engine, move the rod 55 in the direction of the 50 arrow *h*, this will operate the bell crank lever 18 which will operate the connecting rod 12 in the direction of the arrow *k*, this movement will throw the reversing valve 8 over to the opposite side of the explosive 55 chamber 7 as shown by dotted lines. And at the same time the slide 16 will lift the check valve 17 by passing under the head 18, and at the same time will lower the check valve 17' by passing out from under 60 the head 18', thus allowing exploded gases to travel in the opposite direction of the arrow *d*.

While I have shown the invention with one explosive chamber and rotary piston, I 65 can use as many explosive chambers and

rotary pistons as the size of the engine may require.

Having thus described my invention, what I claim as new and desire to secure by Letters Patent, is:

1. In an internal combustion rotary engine the combination of a casing provided with a front and back wall and a water cooling space, an explosive chamber located within said casing between said front and back wall, a reversing valve in said explosive chamber for reversing the travel of the engine, a shaft for said reversing valve, one end of said shaft being journaled in the inner face of said front wall and the other end 70 passing out through said back wall, a lever attached to the end of said shaft that passes out through said back wall, a bell crank lever, a connecting rod attached to said lever and connecting with the bell crank 75 lever, said bell crank lever fulcrumed to a bracket secured to said casing, said lever, connecting rod and bell crank lever for operating said reversing valve, sliding abutments, a sliding bar connected to said bell 80 crank lever for raising and lowering the sliding abutments, and a rod attached to said bell crank lever for operating same.

2. In an internal combustion rotary engine the combination of a casing provided with a front and back wall, an explosive chamber located within said casing and between said front and back wall, a reversing valve placed within said explosive chamber for reversing the travel of the rotary piston, 95 said reversing valve being secured to a shaft, a lever, one end of said shaft being journaled in the inner face of said front wall and the other end passing out through said back wall and connecting with the lever secured thereto, a bell crank lever, a connecting rod attached to said lever and connecting with the bell crank lever, said bell crank lever being fulcrumed in a bracket secured to said casing, sliding abutments, a sliding bar connected with said bell crank lever for raising and lowering said sliding abutments within 100 said casing, and a rod attached to said bell crank lever for operating same.

3. In an internal combustion rotary engine the combination of a casing provided with a front and back wall, an explosive chamber located in said casing between said front and back wall in which is placed and operated a reversing valve for reversing the 115 travel of the rotary piston, a shaft secured to said reversing valve, one end of said shaft being journaled in the inner face of said front wall and the other end passing out through the said back wall, a lever attached 120 to the end of said shaft that passes out through the said back wall, a connecting rod attached to said lever and to a bell crank lever, said bell crank lever fulcrumed to a bracket secured to said casing, a sliding bar 125

connected to said bell crank lever, sliding abutments operated by said sliding bar and bell crank lever.

4. In an internal combustion rotary engine the combination of a casing having a front and back wall, a rotary piston, an explosive chamber located within said casing between said front and back wall, sliding abutments, located within said casing between said front and back wall and on each side of said explosive chamber, packing, said abutments having grooves cut on each end for receiving the packing, pins for securing said packing in said grooves, said sliding abutments having a hole cut therein in which is placed a spiral spring for compressing said packing to the inner face of said front and back wall, a stem secured to said sliding abutments and extending through the casing and a head secured to said stem for receiving a sliding bar, a spiral spring on said stem for compressing said sliding abutments to the rotary piston.

5. In an internal combustion rotary engine the combination of a casing having a front and back wall, an explosive chamber located within said casing between said front and back wall, sliding abutments located in a groove cut in said casing between the front and back wall and on each side of said explosive chamber, grooves cut in each end of said abutments, packing for said grooves, a pin for securing said packing in said grooves, a spiral spring, a hole lengthwise of said abutments in which is placed the spiral spring, said spiral spring to press the packing to the inner face of said front and back wall, a stem secured to said abutments and extending out of said casing, a sliding bar, a head on said stem for receiving the sliding bar, said sliding bar to raise one of said abutments and thereafter to allow the other abutment to drop in when reversing the travel of the rotary piston, a spiral spring on said stem for compressing said abutments to the rotary piston, said abutments when resting on the rotary piston preventing the explosive gases going in the opposite direction of said rotary piston, said casing having an exhaust port for allowing the explosive gases to pass out of the rotary piston chamber.

6. In an internal combustion rotary engine the combination of a casing having a front and back wall with a water cooling space, a rotary piston, an explosive chamber located within said casing between said front and back wall, sliding abutments located within a groove within said casing between said front and back wall and on each side of said explosive chamber, packing, said abutments having grooves on each end for receiving the packing, a pin for securing said packing in said grooves, a hole lengthwise of said abutments in which a spiral

spring is placed, said spiral spring compressing said packing to the inner face of said front and back wall, a stem secured to said abutments and extending out of said casing, a sliding bar, a head on said stem for receiving the sliding bar, said sliding bar operating said abutments, a spiral spring on said stem for compressing said abutments on the rotary piston, said abutments when in place on the rotary piston are for preventing the explosive gases going in the opposite direction from the rotary piston, a spark plug extending through said casing into the explosive chamber, a circuit breaker, said spark plug being connected to a circuit breaker by means of a wire, means for operating said circuit breaker and means for allowing the exploded gases to pass out of the rotary piston chamber.

7. In an internal combustion rotary engine the combination of a casing having a front and back wall, an explosive chamber located within said casing between said front and back wall, sliding abutments located within grooves cut in said casing between said front and back wall, a projection located on said front wall containing a valve chamber in which is placed a bushing and piston valve, said piston valve for compressing the gases within said valve chamber and forcing them through the ports in said valve chamber and into the explosive chamber, a bracket on said front wall for supporting the stem of said piston valve, a spiral spring on said stem to press said stem on a lifting cam, a circuit breaker, the lifting cam operating and controlling the travel of the piston valve and operating the circuit breaker, one section of said circuit breaker being attached to said valve stem and the other section to said front wall, said circuit breaker being connected to the spark plug and generator by wires, and port openings leading from said valve chamber through the inner face of said front wall to the said explosive chamber.

8. In an internal combustion rotary engine the combination of a casing having a front and back wall, an explosive chamber located in said casing between said front and back wall, sliding abutments located in a groove within said casing between said front and back wall, a projection on said front wall containing a valve chamber, a valve for said valve chamber and means for operating said valve, a throttle lever, brackets on said projection for supporting the throttle lever, a valve cam, said throttle lever being attached at the lower end to a strap placed in a groove in the valve cam, and means for operating said throttle lever.

9. In an internal combustion rotary engine the combination of a casing having a front and back wall, an explosive chamber located within said casing between said

front and back wall, sliding abutments within a groove within said casing and between said front and back wall, a drive shaft, said front and back wall forming a bearing for 5 the drive shaft, a rotary piston mounted on said drive shaft, said rotary piston being constructed in four sections, two of said sections being keyed to said drive shaft and forming one portion of said rotary piston 10 and the other two sections being secured to the sections keyed to said drive shaft and forming the remainder of said rotary piston, means for securing said sections together, said rotary piston having pockets formed in 15 the interior where the said sections join, packing placed in grooves cut in the periphery of said rotary piston, said packing being made in right and left sections, said packing in the shape of a right angle with notches 20 cut in the side angle and in line with a groove in the side of said rotary piston, said notches and grooves to fit over a flange on the inner face of said front and back wall, a flat spring and a spiral spring placed 25 within said grooves to keep the upper angles of said packing in contact with the interior of said casing, another spiral spring within a hole in said rotary piston to keep the lower angles of said packing in contact with the 30 inner face of said front and back wall and means for oiling said rotary piston.

10. In an internal combustion rotary en-

gine the combination of a casing having a front and back wall, an explosive chamber located within said casing between said 35 front and back wall, sliding abutments located in a groove in said casing between said front and back wall, a drive shaft, said front and back wall forming a bearing for the drive shaft, a rotary piston mounted on 40 said drive shaft, said rotary piston being constructed in four sections, two of said sections being keyed to said drive shaft, the other two sections being removable and secured to said keyed sections by means of 45 bolts, packing placed in grooves cut in the periphery and down the sides of said removable sections, said packing being in right and left sections and rightangular in shape, the upper angle fitting in a groove in the 50 periphery of said removable section while the side angle fits in a groove on the side of said removable sections, a flat spring and a spiral spring placed under the upper angle and within said groove for keeping said 55 upper angle in contact with the inner radius of said casing, another spiral spring within a hole in said rotary piston for keeping the sides of said packing in contact with the inner walls of said casing.
